SAFETY RAZOR

William L. Mills, Waco, Tex.

Application June 21, 1944, Serial No. 541,386

2 Claims. (Cl. 30—69)

1

This invention relates to a safety razor.

It is particularly aimed to provide a novel construction which is provided with means enabling it to be accurately adjusted to the correct position for shaving, a construction wherein an adjustable guard roller and mounting means is employed, and further, a construction in which a novel handle is used to promote the adjustment of the parts to correct shaving position.

The more specific objects and advantages will become apparent from a consideration of the description following taken in connection with accompanying drawings illustrating an operative embodiment.

In said drawings:

Figure 1 is a view in side elevation, showing the improved safety razor;

Figure 2 is an enlarged section taken on the line 2—2 of Figure 1;

Figure 3 is a horizontal section taken on the line 3—3 of Figure 2;

Figure 4 is a horizontal section taken on the line 4—4 of Figure 3; and

Figure 5 is a vertical section taken on the line 5—5 of Figure 2.

Referring specifically to the drawings, a guard plate is employed at 10, having the usual guard teeth 11 along the lower edge thereof.

Coacting with the guard plate is a clamping plate 12 provided with a pair of lugs 13 integral therewith and adapted to occupy openings 14, for registering therewith, and located in the guard plate 10.

In addition, a screw-threaded stud extends rearwardly from the clamping plate through an opening 16 in the guard plate and in the rear of the latter, extends removably through a terminal 17 of a handle 18. A nut of any suitable shape is employed at 19, being threaded on the stud 15 and movable against the terminal 17 in order to rigidly fasten the parts in operative position.

A blade is employed at 20, having a cutting edge 21 at the proper position for coaction with the clamping plate and guard plate. Such blade may be of any desired shape but is preferably of a form enabling insertion or removal upon slight loosening of the nut 19. To this end, the upper edges of the blade 20 are provided with notches 22 which engage the lugs 13 and stud 15.

It will be noted that the handle 18 is of a unique form in order to provide a relatively large gripping portion as shown having a convex surface adjacent one end as at 23 and a downwardly extending surface 24 adjacent the free end. This construction enables the blade to be better

2

gripped and the razor held and operated at any desired angle and in the best position for comfortable and satisfactory shaving.

The invention also provides a roller 25 which serves as a guard by contacting the skin in advance of the cutting edge 21, such roller extending the full length of the blade and being adjustable toward and away from such blade and transversely with respect to the cutting edge 21.

10 To this end, the guard roller 25 has trunnions 26 which are loosely journaled in plates 27.

The guard plate 10 has rearwardly extending wings 28 at each end thereof to which the side plates 27 are adjustably and removably disposed.

15 Such side plates have open slots 29 in their upper ends through which fastening screws 30 are passed which are threaded in openings 31 in the wings 28. Such screws 30 also preferably pass through washers at 32.

It will be realized that through the adjustment of the screws 30, the side plates 27 may be moved to various positions to accurately adjust the position of the guard roll 25. Also, they enable the guide plates 27 and guard rolls 25 to be completely removed if the user desires.

Various changes may be resorted to provided they fall within the spirit and scope of the invention.

I claim as my invention:

30 1. In a razor having a guard plate, a clamping plate, and a stud and lugs on the clamping plate occupying openings in the guard plate, a handle having a terminal through which the stud passes, fastening means on the stud engageable against the terminal, a guard roller, means mounting said guard roller in operative position to the cutting edge of the blade, comprising side plates in which the roller is journaled, and means rotatably and slidably securing the side plates to the guard plate.

35 2. A razor of the class described having a guard plate, a clamping plate to secure a razor blade against the guard plate, lugs on the clamping plate occupying openings in the guard plate, a screw stud passing from the clamping plate through an opening in the guard plate, a handle having a terminal through which the stud passes, fastening means on the stud engageable against the terminal, a guard roller, means

40 45 mounting said guard roller in operative position to the cutting edge of the blade, comprising side plates in which the roller is journaled, means securing the side plates to the guard plate, comprising screws, said guard plate having wings 40 against which the side plates are disposed, said

50 55

side plates each having a slot, and one of said screws passing through each of the slots and being threaded to one of said wings.

WILLIAM L. MILLS.
